BRINE AND EROSION CONTROL FOR RAILROADS

Application filed February 4, 1929. Serial No. 337,499.

This invention relates to refrigerator cars and has particular reference to the provision of means for controlling the discharge of brine or the like from refrigerator cars.

5 An object of this invention is to eliminate the continuous drip of brine and salt solution from refrigerator cars, to thus eliminate the detrimental effect of this brine on the right-of-way and rolling stock of railroads.

10 A further object of this invention is to provide a construction of the above character which will require little or no attention in operation, which will be simple in construction, and which may be economically installed 15 on present equipment or built into the car during the construction of the same.

Other objects and advantages of this invention will become apparent as the following description proceeds, particularly when 20 reference is had to the accompanying drawings wherein

Figure 1 is a fragmentary semi-diagrammatic sectional view through a refrigerator car showing the invention applied to the 25 same;

Figure 2 is an enlarged fragmentary sectional view through a portion of the car shown in Figure 1;

Figure 3 is an elevational view of a part of 30 the mechanism shown in Figure 1;

Figure 4 is a vertical sectional view taken substantially on the line 4-4 of Figure 3;

Figure 5 is a fragmentary sectional view through one of the valves used in the construction, and

Figure 6 is a fragmentary sectional view through a slightly modified form of construction.

Heretofore in the use of refrigerator cars 40 it has been customary to permit the brine from the car to be discharged continuously during the travel of the car. It is well known that the brine or salt solution quickly corrodes metals and it has been found that the 45 continuous salt spray to which the right-of-way and rolling stock of railroads, on which refrigerator cars are moved has been subjected is highly detrimental to the rails and equipment and is one direct cause for large 50 expenditures for replacements. Further, the

resulting deterioration of the right-of-way and rolling stock has undoubtedly been the cause of numerous accidents, since the gradual weakening of the metal structures has not always been apparent on the surface. 55

In order to eliminate this difficulty, attempts have been made to substitute electrical or mechanical refrigeration units for the ice compartments used as standard equipment on most refrigerator cars, but has been 60 found that such a substitution has involved so much expense as to be substantially impractical. The present invention therefore contemplates the elimination of the above mentioned difficulty by means whereby the 65 brine discharge may be automatically controlled and deposited at certain definite points, thus eliminating entirely the spraying of the brine on the right-of-way and the back wash of the brine on the frame structure of 70 the cars when the train is in motion.

A typical run of refrigerator cars on one major road, consists of approximately 330 miles of track, with nine definite time card stops, between terminals. During the time 75 of year when the maximum amount of ice melt occurs, 4,000 pounds of ice is required per car for this run. This quantity of ice reduced to liquid is equivalent to approximately 500 gallons per car, making the ratio 80 of melt per mile of run approximately 1½ gallons. On the typical run in question the longest mileage between stops is 90 miles, providing no emergency stops are made, there would be therefore, 90 times 1½ gallons or 130 85 gallons of solution per car to control.

Using the above figures as a practical basis, the present invention contemplates the provision of means for conducting the drip from the ice and salt compartments of the refrigerator car through suitable drain pipes to a storage tank secured to the under frame of the car chassis. Thus the brine will be prevented from spraying on the right-of-way of the railroad and the back wash of the spray 95 on to the frame work of the car would be entirely eliminated. By providing means for discharging the brine from the storage tank at certain definite points, the condition of the tracks at these points could be carefully 100

guarded, and the danger of weak track structure entirely eliminated. While the invention will find utility on any railroad, it will find particular utility on a road where metallic ties are used, since these ties are generally quite seriously affected by the action of the brine solution.

Referring then particularly to the drawings wherein a preferred embodiment of the inventive idea is disclosed, there is semi-diagrammatically illustrated in Figure 1 a refrigerator car 10 having the axles 11 and the wheels 12. The car may be of any desired construction and as illustrated may be provided with the ice compartments 13 and 14 located at its opposite ends.

In use it is customary to pack the ice compartments 13 and 14 with ice and salt and to permit the brine drip from these compartments to be discharged continuously through the bottom of the compartments during travel of the car. As brought out before, this causes a spraying of the right-of-way with the brine solution and also causes a spraying of the under frame of the car by back wash while the car is in motion. The present invention eliminates this spraying effect by collecting the brine discharged from the ice compartments and by storing the same in a suitable storage tank to be discharged at predetermined points in the travel of the car.

Referring then particularly to Figure 2 of the drawing, it will be noted that there is provided in the bottom of the ice compartment 13 a sump 15 in which the brine solution collects. A similar sump is formed in the ice compartment 14 and these sumps are connected by drain lines 16 and 17 respectively to a storage tank 18 secured to the framework of the car chassis. As illustrated, this storage tank may be conveniently located at substantially the center of the car, thus being spaced at equal distances from the ice compartments.

For controlling the discharge of the brine from the storage tank there may be provided a discharge fitting 19 controlled by a butterfly valve 20 fixed to an actuating shaft 21. A collar 22 fixed to the shaft 21 is provided with an operating arm 23 whereby movement of the said arm 23 will effect a rotation of the shaft 21 to actuate the valve.

For automatically controlling the actuation of the valve 20 there is provided a mechanism designated generally by the reference character 25. This mechanism includes a fly wheel 26 fixed to a shaft 27 mounted in suitable bearings 28 secured to the under frame structure of the car. The shaft 27 is driven from one of the car axles 11 by any suitable mechanism such for example as a chain 29 engageable with gears 30 and 31 mounted on the axle 11 and shaft 27 respectively.

Pivottally mounted between ears 32 projecting laterally from one face of the fly

wheel 26 at diametrically opposite points are bell crank levers 33. These bell crank levers are formed at one end with the weights 34, and these weights are normally urged inwardly toward the shaft 27 by the springs 35. The other end of each bell crank lever is formed with a pin 36 adapted to engage in a groove 37 formed in a sleeve 38 slidably mounted on the shaft 27. It will be obvious that upon rotation of the fly wheel 26 centrifugal force will cause the weights 34 to swing outwardly, thus moving the sleeve longitudinally of the shaft 27.

Pivoted as at 40 to the under frame of the car structure is a lever 41 provided at its one end with a yoke 42 adapted for engagement in a second groove 43 formed in the sleeve 38. The lever 41 is bent as at 44 to extend downwardly below the tank 18 and is then bent forwardly as at 45 to form the extension 46 engageable with the valve actuating arm 23 as at 47. The arrangement is such that when the weights 34 are in their outermost position under the action of centrifugal force, the lever 41 will be moved about its pivot to close the valve 20. When on the other hand rotation of the fly wheel 26 is stopped the weights 34 will be drawn inwardly toward the shaft 27 to shift the collar 28 and lever 41 to effect an opening of the valve 20.

From the above it is believed that the structure and operation of this form of the invention will be readily understood. All of the brine dripping from the ice compartments will be collected in the storage tank 18. When the car is at rest the valve is held open so that during the loading of the ice compartments there will be no accumulation of drip in the tank. As soon as the car is set in motion the fly wheel 26 is driven from the axle 11 whereupon the weights 34 move outwardly to shift the sleeve 38 and lever 41 to close the valve 20. The operating mechanism is so designed that it will operate properly, regardless of the direction in which the car is moved and is of such a construction that it may be quickly and easily installed on any refrigerator car, regardless of the construction of the same.

The power required to operate the control mechanism will be extremely slight and the weights may be so arranged as to operate at any speed at which the car may travel. When the weights 34 fly outwardly to their maximum outward position, they remain at rest in this position during travel of the car, so that there are practically no moving parts to the control mechanism during the major portion of its use. Obviously, whenever the car is stopped which as brought out before is usually nine times during a run of 330 miles, the valve 20 will be automatically opened to permit the discharge of the brine from the storage tank. When, however, the car is set in

motion the drain valve is automatically closed so that all drip is accumulated in the storage tank, thus entirely eliminating the spraying of the right-of-way of the railroad and the spraying of the frame structure of the car by back wash of the brine.

While the control has been described as being actuated by a centrifugally driven member, it will be readily apparent that the control might be automatically actuated in a number of other ways. For example, the lever 41 might conveniently be operatively connected in any suitable manner to the reciprocating plunger rods of the usual or standard air brake system of the car, the arrangement being such that upon actuation of the air braking system the valve 20 will be operated. Further it will be obvious that the valve 20 might be manually controlled and be opened by an attendant whenever the car makes a stop.

By reference to Figure 2 of the drawing it will be noted that the drain line 16 is provided adjacent the sump 15 with a manually controlled valve 51. It will also be noted that there is provided a second drain line 52 which discharges directly from the sump 15 and that this drain line is controlled by a manually operated valve 53. This construction is provided, since it has been found that in order to maintain the correct temperature to suit the commodity carried, it is the practice at certain times to use plain ice in the ice compartments. As the drip from the ice is not corrosive, it may be discharged directly from the ice compartment by closing valve 51 and opening valve 53. This method would find particular utility during freezing weather.

Instead of providing a separate storage tank 18 mounted as illustrated adjacent the center of the car the lower section of each ice compartment may be constructed to act as a storage receptacle and discharge valves operated either manually or automatically may be provided to drain these storage units. Such a construction is shown in Figure 6, wherein 13^a designates one of the ice compartments. This compartment is provided, as illustrated, with the lower compartment 60 into which the brine drains through the sump 61. The compartment 60 may be provided with the discharge fitting 62 manually controlled by the valve 63, this fitting being similar to the drain line 52 above described. The compartment 60 may also be provided with the manually and automatically controlled discharge fitting 64 having the manually controlled valve 65 and the automatically controlled valve 66. It will be obvious that the lever 67 provided for actuating the valve 66 may be connected either to a centrifugal mechanism such as above described or to the air brake system such as also above described. Thus the brine may be collected in the compartment

60 and either discharged directly from this compartment during the travel of the car or else discharged periodically from this compartment through the fitting 64.

While the invention has been described with considerable detail, it is to be clearly understood that the description is for the purposes of illustration only. The right is therefore reserved to make such changes in the details of construction and arrangement of parts as will fall within the purview of the attached claims.

What I claim as my invention is:

1. The combination with a refrigerator car having an ice compartment, of a storage tank for collecting the brine discharged from the ice compartment while the car is in motion, and means operable upon a stopping of the said car for effecting a discharge of the brine from the said storage tank.

2. The combination with a refrigerator car having an ice compartment, of a tank for receiving the brine discharged from the said ice compartment, a valve for controlling the discharge of brine from the tank, and means operable in dependence upon the movement of the car for actuating the said valve.

3. The combination with a refrigerator car having an ice compartment, of a tank for receiving the brine discharged from the said ice compartment, a valve for controlling the discharge of brine from the tank, and means controlled by movement of the said car for closing the valve when the car is in motion and for opening the valve when the car is stopped.

4. The combination with a refrigerator car having an ice compartment, of a tank for receiving the brine discharged from the said ice compartment, a valve for controlling the discharge of brine from the tank, and means controlled by movement of the said car for closing the valve when the car is in motion and for opening the valve when the car is stopped, said means including a centrifugally operated mechanism and a connection between said mechanism and the valve.

5. The combination with a refrigerator car having a rotatable axle and an ice compartment, of a tank for receiving the brine discharged from the ice compartment, a valve for controlling the discharge of brine from the tank, a driven shaft, a driving connection between said rotatable axle and said driven shaft, a flywheel on said driven shaft, members carried by said flywheel movable by centrifugal force upon rotation of said flywheel, and means connecting said members to said valve for actuating the latter upon movement of the former.

6. The combination with a refrigerator car having an ice compartment, of a tank for receiving the brine discharged from said ice compartment, a normally open valve for controlling the discharge of brine from said

tank, and means for closing said valve while the car is in motion, said means including a rotatable member connected to a moving part of said car whereby the same is driven when the car is in motion, weights carried by said rotatable member adapted to be moved by centrifugal force when the said member is rotated and a connection between said weights and said valve for moving the latter from the former.

10 In testimony whereof I affix my signature.
ROY E. WING.
